ATTORNEY

UNITED STATES PATENT OFFICE.

HANS K. LORENTZEN, OF NEW YORK, N. Y.

RECEPTACLE CLOSURE.

Application filed April 20, 1927. Serial No. 185,089.

This invention relates to a receptacle closure, and aims particularly to improve the construction of hinged lids.

The invention provides a structure in which 5 spring means are used to bias the lid toward the rear of the receptacle and thereby maintain an automatically tight frictional contact between the forward edges of the lid and receptacle.

10 A further feature of the invention resides in utilizing these same spring means for holding the lid in open position.

Additional objects and advantages will appear as the description proceeds.

15 While a preferred embodiment of the invention has been disclosed for purposes of illustration, it should be understood that various changes may be made in the structure without departing from the spirit and scope 20 of the invention as hereinafter set forth and claimed.

In the drawings:

Fig. 1 is a plan of a box embodying the invention, parts being broken away.

25 Fig. 2 is a front elevation of the box.

Fig. 3 is an end elevation of the box.

Fig. 4 is a fragmentary perspective of the lid.

30 Fig. 5 is a fragmentary perspective of the box.

Fig. 6 is a section on line 6—6 of Fig. 1.

Fig. 7 is a section on line 7—7 of Fig. 1.

Referring to the drawings more particularly, the reference numeral 10 indicates a box 35 formed of metal or other suitable material having end walls 11, a front wall 12 and a rear wall 13. The upper edges of the front and end walls carry an outwardly-curved rounded bead 14.

40 The upper edge of the rear wall is formed at its central part with a rearwardly and downwardly extending lip 15, and with lips 16 spaced from lip 15. The lips 16 merge into the rim 14 and are longer than the lip 15 and 45 carry inwardly directed angular flanges 17.

The closure lid 18 is provided with a rounded overhanging flange 19 adapted to fit over the bead 14, and carries at the center of its forward edge a rigid clip 20 with a locking indent 20^a for engagement beneath the bead 14. At the rear side of the lid the flange 19 is extended and bent inwardly at 21, the extension being formed with laterally projecting hinge members 22.

55 When the lid is in place on the box the hinge members extend under the lips 16 as

will be clear from Fig. 1. An opening 23 is formed through the lower rear corner of the box just below the interval between each lip 16 and the lip 15, and a flat spring 24 is 60 fastened to the bottom of the box and extends through the aperture 23 to engage against the inner face of extension 21 (Fig. 6).

In the structure above set forth the springs 24 at all times press the hinge members 22 65 back toward the flanges 17, although when the lid is closed (Fig. 6) the engagement of the clip 20 over the forward edge of bead 14 pulls the lid to the front against the pressure of the springs and keeps hinge members 21 70 out of contact with the flanges 17. During opening movement of the lid the springs press the hinge members against the flanges 17 causing them to pivot in the angle formed between the lips 16 and the flanges 17. Due 75 to these features of construction the clip 20 is always pressed firmly back against the bead 14 when the box is closed, and since rearward movement of the lid is limited solely by engagement between the forward edges of the 80 box and lid, wear is automatically taken up and the lid remains firmly closed. At the same time the springs serve to hold the lid in the opened position of Fig. 6, in which position the inner side of the hinge members 22 85 engage the inner side of flange 16 and the part of lid flange 19 lying just above the extensions 22 engages the flange 17. (See Fig. 7.)

The inturned flanges 17 keep the hinge members 22 from working down.

90 Due to the arrangement and leverage of the parts, the springs furnish only a moderately light resistance to opening and closing movements of the lid.

I claim:—

1. In combination, a box, a lid fitting over the box, a flange extending downwardly from the rear edge of the lid, angular lips carried by the box and adapted to engage parts carried by the flange during swinging movement of the lid, a part carried by the box and engaging the flange to limit opening movement of the lid, and spring means engaging the flange and biasing it rearwardly toward the angular extensions.

2. In combination, a box, lips extending rearwardly from the rear edge of the box, said lips having inwardly directed angular extensions, a lid fitting over the box, the forward edge of the lid having a flange engaging the forward edge of the box when the lid is closed, a flange extending downwardly

from the rear edge of the lid, hinge members projecting laterally from the flange and adapted to extend behind the angular extensions, and spring means biasing the hinge members rearwardly toward the angular extensions.

3. In combination a box, lips extending rearwardly from the rear edge of the box, said lips having inwardly directed angular 10 extensions, a lid fitting over the box, the forward edge of the lid having a flange engaging the forward edge of the box when the lid is closed, a flange extending downwardly from the rear edge of the lid, hinge 15 members projecting laterally from the flange and adapted to extend behind the angular extensions, spring means biasing the hinge members rearwardly toward the angular extensions, parts of the lid being adapted to 20 engage the outside of the angular extensions when the lid is in open position.

4. In combination, a box, a lid fitting over the box, a flange extending downwardly from the rear edge of the lid, hinge members extending laterally from the lower edge of 25 the flange, angular lips carried by the box and adapted to engage the hinge members, and spring means for biasing the lid to the rear to cause the hinge members to engage the lips.

5. In combination, a box having a rear wall, a lid fitting over the box, a flange extending downwardly from the rear edge of the lid, hinge members extending laterally from the lower edge of the flange, angular 30 lips spaced rearwardly from the rear wall of the box and extending over the hinge members, and spring means for biasing the lid to the rear to cause the hinge members to engage the lips.

In testimony whereof I affix my signature.

HANS K. LORENTZEN.
